UNITED STATES PATENT OFFICE.

AXEL W. HAWKINSON, OF WASHINGTON, PENNSYLVANIA, ASSIGNOR TO TOPLIFF-ELY COMPANY, OF WASHINGTON, PENNSYLVANIA.

HOOD FOR CHILDREN'S CARRIAGES AND DOLL CARTS.

Application filed January 24, 1922. Serial No. 531,414.

To all whom it may concern:

Be it known that I, AXEL W. HAWKINSON, a citizen of the United States, and a resident of Washington, in the county of 5 Washington and State of Pennsylvania, have invented certain new and useful Improvements in Hoods for Children's Carriages and Doll Carts; and I do hereby declare the following to be a full, clear, and 10 exact description of the invention, such as will enable others skilled in the art to which it appertains to make and use the same.

This invention relates to improvements in 15 hoods for children's carriages or doll carts, and more particularly to that type which comprises a loom-woven reed body portion supported by bows,—one object of the invention being to provide a hood structure of the type specified in which the woven 20 reed body portion shall be supported by metal, preferably steel, bows in such manner that the edges of the woven reed at respective ends of the hood shall be effectually covered, and so that the woven reed 25 body portion shall be securely fastened to the metal bow-frame.

With this and other objects in view, the invention consists in certain novel features 30 of construction and combinations of parts as hereinafter set forth and pointed out in the claims.

In the accompanying drawings; Figure 1 is a perspective view of a hood embodying 35 my improvements; Figure 2 is a view partly in section and partly in elevation showing the metal frame construction, and Figure 3, 4 and 5 are fragmentary sectional views.

The frame of my improved hood includes 40 in its structure, two metal (preferably steel) bows 1 and 2, each securely riveted at its ends to approximately triangular metal brackets 3, 3,—said bows being disposed preferably at approximately right angles to each other. At points removed from the 45 brackets 3, the two bows are connected by metal braces 4 which are preferably curved.

Respective end portions of the woven reed 50 body portion 5 of the hood are secured by rivets 6 to the inner faces of the bows 1 and 2, said rivets passing through holes 7 in the bows, and the curved side edge portions of the body 5 are riveted to the braces 4 as indicated at 8. To facilitate the securing of the woven reed body to the bows 1 and 2,

said body may first be placed upon a suitable form and the frame bows 1 and 2 and the braces 4 riveted to its edge portions and the rough edges of the reed body will then be trimmed even with the outer edges of said bows and braces. Inner bows 9, 10 will be 55 located inside the edge front and back edge portions of the reed body so as to lie parallel with the respective bows 1 and 2 and are secured in place by rivets 11 passing through holes 12 in said inner bows, through the 60 reed body and through holes 13 in the bows 1 and 2. Each inner bow is provided at one edge with a flange 14, which is disposed to cover the end edges of the fiber of the reed 65 body member 5.

If desired, inner strips 15 may be placed against the curved side portions of the reed body and these strips may be held in place by the rivets 8.

Having fully described my invention what 75 I claim as new and desire to secure by Letters-Patent, is:—

1. A hood of the character described comprising a woven reed body, outer metal bows disposed upon the exterior of said woven 80 reed body along the front and rear margins thereof, inner metal bows disposed against the inner surface of the body along the marginal front and rear portion of said woven reed body, and fastening means securing 85 said bows in place, said inner bows each having a flange at its outer edge lying across and abutting the front and rear marginal edges of the woven reed body.

2. A hood of the character described comprising two pairs of metal bows disposed at an angle to each other, a woven reed body member having its front and rear marginal portions disposed between the bows of the 90 respective pairs, one bow of each pair having a flange lying across the adjacent marginal edge of the body member, and fastening devices whereby the bows of each pair are secured to the woven reed body member and to each other and the edges of the body will 95 be housed flat between the bows.

3. A hood of the character described comprising two bows disposed at an angle to each other, brackets connecting the adjacent 100 ends of said bows, braces connecting side portions of said bows in proximity to said brackets, a body member secured along its marginal edges to said bows and braces,

mating bows and braces also secured along the marginal portions of the body, the edges of the body being received between the opposed faces of the corresponding bows and braces, one set of bows having flanges along their outer edges extending across the edges of the reed body.

In testimony whereof, I have signed this specification in the presence of two subscribing witnesses.

AXEL W. HAWKINSON.
